UNITED STATES PATENT OFFICE

153,401

DESIGN FOR A PICTURE FRAME

Duane Swibold, Royal Oak, Mich.

Application October 25, 1946, Serial No. 134,247

Term of patent 14 years

(Cl. D29—20)

To all whom it may concern:

Be it known that I, Duane Swibold, a citizen of the United States of America, and residing at Royal Oak, county of Oakland, State of Michigan, have invented a new, original, and ornamental Design for a Picture Frame, of which the following is a specification, reference being made to the accompanying drawings, forming part thereof.

The opposite side and back, not shown, are the same in appearance as the front and side shown.

I claim:

The ornamental design for a picture frame, substantially as shown and described.

DUANE SWIBOLD.
